UNITED STATES PATENT OFFICE.

GEORGE H. MINIER AND THADDEUS LOWE, OF SOUTH PASADENA, CALIFORNIA.

DESIGN FOR A HEATER-CASING.

40,980.

Specification for Design.

Patented Nov. 8, 1910.

Application filed August 27, 1910. Serial No. 579,357. Term of patent 14 years.

To all whom it may concern:

Be it known that we, GEORGE H. MINIER and THADDEUS LOWE, citizens of the United States, residing at South Pasadena, in the county of Los Angeles and State of California, have invented a new, original, and ornamental Design for a Heater-Casing, of which the following is a specification, reference being had therein to the accompanying drawing, forming part thereof.

The figure is a perspective view of a heater casing showing our new design.

Our design is a heater casing which is substantially rectangular in shape, and having niches formed at the corners and a pillar in each niche. The upper portion of the

heater casing is trimmed with beading and the lower portion is trimmed with beading and a panel of lattice work. Ornamental knobs are placed upon the front of the heater.

We claim:

The ornamental design for a heater as shown and described.

In testimony whereof we hereunto affix our signatures in presence of two witnesses.

GEORGE H. MINIER.
THADDEUS LOWE.
